No 1615.

S.A. HOLMES.

Witnesses,

Design for the background of Photographic Pictures. City of New York July 7th 1862

W W Rush Patented Aug. 5. 1862 Silas Atbaland

Chas H. Smith

Dec. 1615

Silas A. Holmes, of Brooklyn, N.Y.
Letters Patent No. 1615, dated Aug. 5, 1862,

The schedule referred to in these Letters Patent and making part of the same.

To all whom it may concern:

Be it known that I, Silas A. Holmes, of Brooklyn
in the County of Kings and State of New York, have invented and
applied to use a certain new and ornamental Design for the Background
of Photographic pictures, and I do hereby declare the following to be a full
and clear description of the same, reference being had to the annexed
specimens showing the said ornamental background behind the figures
photographed.

2

Mar. 16 15

My new ornamental design consists in a floor painted in perspective on the screen or background placed behind the person or article to be photographed, said floor corresponding generally with the actual floor sustaining the object to be photographed, whereby the design of the floor painted or otherwise formed on said screen gives the ornamental appearance in the photographic picture of the figure standing off at some distance from the background.

In the specimens attached, the point at which the screen and floor unite are marked a. a., the ornamental design of the screen being above that point, and the oil cloth on the floor showing in said specimens below that point.

The ornamental design of the screen represents a vaulted room with the aforesaid floor represented in perspective.

What I claim and desire to secure by Letters Patent is the ornamental design of a floor in perspective upon the screen or background for photographic pictures as shown.

I also claim the ornamental design of the vaulted room as shown for the screen or background for photographic pictures.

In witness whereof I have hereunto set my signature this Twenty ninth day of March, 1862.
